UNITED STATES PATENT OFFICE

1,998,025

AIR COMPRESSOR

Russell John Reaney, Ottawa, Ontario, Canada

Application November 5, 1928, Serial No. 317,399
Renewed August 29, 1934

8 Claims. (Cl. 230—192)

This present invention relates to new and useful improvements in an air compressor and has for its primary object the provision of an improved and simplified structure including cylinders and pistons within a main compressed air tank, with the pistons and one of the cylinders adapted for reciprocation while the other cylinders remain stationary within said main compressed air tank.

Another object of the invention resides in the provision of an air compressor of the character stated, which is of such construction and operation as to provide for several compressing operations on the air charges drawn in from the surrounding atmosphere during operation of the device.

The invention has for a further object the provision of an air compressor of the character stated, which is composed of the minimum number of parts, of simple construction and operation and in which changing from open to closed position and vice versa of the several slide valves for the cylinders and air conducting tubes is automatically accomplished at the end of each stroke of the reciprocating pistons.

To the accomplishment of these and related objects, as will become apparent as the description proceeds, my invention resides in the construction, combination and arrangement of parts as shall be hereinafter more fully described, illustrated in the accompanying drawings and pointed out in the claims hereunto appended.

The invention will be best understood and can be more clearly described, when reference is had to the drawings, forming a part of this disclosure and wherein like characters indicate like parts throughout the several parts.

In the drawings:—

Figure 1 is a longitudinal section through the improved air compressor with the operative parts shown in initial positions;

Figure 2 is a view similar to Figure 1, showing the position of the operative parts at the end of the first stroke of the reciprocating pistons;

Figure 3 is a plan of one of the automatic slide valves employed;

Figure 4 is a longitudinal section through the valve, substantially as taken on the plan of line 4—4 of Figure 3, looking in the direction indicated by the arrows;

Figure 5 is a perspective view of another type of automatic slide valve employed;

Figure 6 is a longitudinal section through the second type of valve shown in Figure 5.

Referring more in detail to the drawings, it

will be noted that the main compressed air tank 11, has a compressed air service pipe 12 leading therefrom, at a point near the far or rear end thereof, the service pipe 12, carrying a hand controlled valve 13 and a pressure gauge 14 of conventional form. The main compressed air tank 11 is provided with a forward head 15 and a rear head 16, threaded or otherwise firmly secured on the opposite ends thereof. A double bracket 17 is carried on the outer face of the forward head 15 with the legs of the bracket converging, then turned toward one another as at 18 and finally having inwardly directed parallel portions 19 slightly spaced apart and extending through the center of the head 15 and 16 into the main compressed air tank 11. The portions 19 of the double bracket 17 serve to support centrally in the main compressed air tank 11, the pair of spaced and aligned stationary cylinders 20 and 21, the parallel portions 19 connecting with the outer of forward end of the cylinder 20. The opposed ends of the cylinders 20 and 21 are connected by the bar 22 which is preferably integral with said opposed cylinder ends. A stationary air inlet tube 23 projects outwardly or forwardly from the forward head of the stationary cylinder 20, the inner or rear end of the stationary air inlet tube 23 communicating with the interior of the cylinder 20, while the outer or forward end of said stationary tube 23 is open to the surrounding atmosphere. A check valve 24 is carried in the stationary tube 23 to permit atmospheric air to enter the cylinder 20 but prevent air from escaping from the cylinder 20 by way of the stationary tube 23.

An operating handle 25, the operation of which is started and continued by hand or other power applied thereto, transversely straddles the double bracket 17 and has its opposite ends connected with the guide member 26 reciprocating through the central opening 27 of the forward tank head 15. The guide member 26 extends outwardly from the center of the forward head or end 28 of the elongated reciprocating cylinder 29 and encircles the parallel inwardly directed portion 19 of the double bracket 17. It is therefore apparent that the operating handle 25 may be employed to operate or reciprocate the cylinder 29. The length of the cylinder 29 is greater than the combined length of the stationary cylinders 20 and 21 and their connecting rod 22, all of which are enclosed by the cylinder 29 which reciprocates over the cylinders 20 and 21 and is further guided by the stationary guide rods 30, projecting

in the main compressed air tank 11 from the rear head 16 thereof and extending through the projecting annular flange 31 of the rear head 32 of the cylinder 29. Appropriate bearing rings 33 are carried circumferentially of the stationary cylinders 20 and 21, near the ends of the latter for snug engagement with the inner circumferential wall of the reciprocating cylinder 29.

Working within the stationary cylinder 20 is the piston 34 carried on the solid piston rod 35, which extends forwardly through the center of the forward head of the cylinder 20 and has its outer end attached to the center of the outer end of the reciprocating guide 26. An appropriate one-way valve 36 is provided in the piston 34. Working within the stationary cylinder 21 is the piston 37 carried on the forward end of the hollow piston stem 38 which has its rear end secured in the rear head 32 of the reciprocating cylinder 29 and opens into the main compressed air tank 11. A one-way valve 39 is provided in the hollow piston rod 38. The compressed air conducting tube 40 has its main portion extending longitudinally of the reciprocating cylinder 29 and its forward end 41 is turned at an angle and extends inwardly through the side of the latter near the longitudinal center of said reciprocating cylinder 29. The rear end 42 of the tube 40 is also shaped parallel to the forward end 41 and ends with the side of the two-way slide valve 43, which in turn is secured in the rear head 32 of the reciprocating cylinder 29. It will therefore be seen that the compressed air conducting tube 40 and the two-way slide valve 43 move with the reciprocating cylinder 29 and the pistons 34 and 37 and their respective piston rods 35 and 38 during operation of the air compressor.

Secured in the rear head 16 of the main compressed air tank 11 and projecting inwardly therefrom is the valve operating member 44 in alignment with the two-way slide valve 43 and engaged by the latter when the reciprocating cylinder 29 is in its rearwardmost position or at the end of its rearward stroke. A slide valve 45 is carried in the rear head of the stationary cylinder 21 and in alignment with the two way slide valve 43. A similar slide valve 46 is also in alignment with the two-way slide valve 43 and slide valve 45 and is carried in the forward head of the stationary cylinder 21. Another slide valve 47 is carried in the rear head of the forward stationary cylinder 20 and in alignment with the two-way slide valve 43, slide valve 45 and slide valve 46. The purpose of thus arranging these several valves 43, 45, 46 and 47 will later appear. Carried in the opposite portion of the rear head of the stationary cylinder 20 is a check valve 48 which, when opened, forms communication between the interior of the cylinder 20 and the compressed air chamber 49, between the cylinders 20 and 21 and within the reciprocating cylinder 29.

A further check valve 50 is provided in the rear head of the stationary cylinder 21 and which check valve 50, when opened, provides communication between the interior of the stationary cylinder 21 and the rear end portion of the reciprocating cylinder 29.

The construction and operation of the two-way slide valve 43 may be readily apparent from Figures 3 and 4, in which it will be seen that the valve body has a longitudinal air passage 51 opening on the outer end thereof and leading to

the connecting passage 52 in the slide plate 53 of the valve and which connecting passage 52 forms communication between the passage 51 and the second passage 54, leading to the interior of the reciprocating cylinder 29, at the rear end thereof, thus providing for passage of the compressed air from the main compressed air tank 11 into the rear end of the reciprocating cylinder 29 between the rear head 32 thereof and the rear head of the stationary cylinder 21. When the slide plate 53 is in its other extreme position, the compressed air passage 55 thereof is brought into communication with the air passage 54 and the transverse air passage 56, in the body of the valve 43 and which passage 56 leads to the turned end 42 of the compressed air conducting tube 40, thus opening communication between the interior of the reciprocating cylinder 29 and this end 42 of the said air conducting tube 40. The slide plate 53 has a pin 57 extending transversely therethrough and working in an elongated longitudinal slot 58 in one end of the body of the valve and a second pin or plunger 59 works longitudinally through the body of the valve and projects from the other end thereof. This second pin or plunger 59 has a head 60 provided on its inner end and engaged with the side of the depending free end and the pin 59, within the end pocket 61 formed in the valve body and having communication at its side with the slot 58. A head 62 is provided at the other end of the pin 57, and bears against the under face of an angular bracket plate 63 carried on the body of the valve 43 and extended at an angle across same, opposite end in spaced parallel relation to the slide plate 53. An appropriate expansion spring 64 is engaged around the driving pin 57 between the head 62 thereof, and the outer face of the slide plate 53 and bearing thereon to resiliently retain the slide plate 53 in closed or air-tight engagement with the portion of the body of the valve on which it operates.

From Figures 5 and 6, the construction and operation of the other type or form of slide valves employed by the applicant and designated as valves 45, 46, and 47, may be readily apparent. As these valves are of similar construction and operation, only valve 45 is illustrated and will be described in detail. The body of the valve 45 is of elongated form and provided with an exteriorly threaded portion 65, similar to the two-way slide valve 43 and also includes a slide plate 66 working on the flattened portion 67 of the valve body and having a pin 68 extended through the slide plate 66, through the elongated longitudinal guide slot 69 therefor in the valve body and into the end pocket 70 thereof. One end of the slide plate 66 projects past the end of the valve body for engagement with an opening member to move the slide plate 66 inwardly to its innermost position while movement of the slide plate 66 to its outermost position is effected by the second pin or plunger 71 which works longitudinally in the valve body and extends from the opposite end thereof, the head 72 on the inner end of the plunger 71 engaging the side of the pin 68 within the pocket 70. The head 73, on the outer end of the pin 68 engages the under face of the angular bracket 74, carried on the body of the valve 45 and having its free angular portions in spaced parallel position to the slide plate 66 and outwardly thereof. The expansion spring 75 encircling the pin 68 between the head 73 thereof and the outer face of the slide plate 66 and bearing on the latter serves to resiliently retain the valve plate 66 in close

and air-tight contact with the valve body. In this form of the valve, only a single air passage 76 is required in the valve body, extending longitudinally thereof from one end and then turned to open on the flat side face of the valve body. When the slide plate 66 is in one of its extreme positions, the valve slot 77 thereof, registers with the turned end of the air passage 76 in the valve body and thus the valve is open when in this position. When the slide plate 66 is in its other extreme position, the turned end of the air passage 76 through the valve body is covered and thus the valve is closed when the slide plate 66 is in this position.

As the construction of the device has thus been described in detail, brief reference is now had to its use and modus operandi: There is originally within the stationary cylinders 20 and 21, the reciprocating cylinder 29 and the air chamber 49, air under atmospheric pressure, and the reciprocating cylinder 29 is occupying its outermost or forwardmost position, as shown in Figure 1. When the reciprocating cylinder 29 is in this position, the valve 43 is in position to provide communication between the interior of the main compressed air tank 11 and the rear end of the reciprocating cylinder 29. The valve 45 is closed; the valve 46 is open; and the valve 47 is closed. All the check valves 24, 36, 48, 39 and 47 are always normally closed, but free to open or operate as required. The reciprocating cylinder 29 is now reciprocated by the operating handle 25, for starting the air compressor. As the reciprocating cylinder 29 makes its rearward or inward stroke, the compressed air passes from the main compressed air tank 11 through the valve 43 and into the rear end of the reciprocating cylinder 29. At the same time atmospheric air is drawn through the tube 23 into the forward end of the stationary cylinder 20, forwardly of the piston 34. At the same time the air in the cylinder 20 passes through the valve 48 into the air chamber 49. From within the air chamber 49, air may pass into the forward end of the stationary cylinder 21, forwardly of the piston 37, by way of the open valve 46. The valve 43 is at this time open into the rear end of the reciprocating cylinder 29, between the rear head 32 of the latter and the rear head of the stationary cylinder 21. During rearward movement of the reciprocating cylinder 29, valves 48 and 50 open under influence of air pressure in the respective stationary cylinders 20 and 21, thus permitting the air to discharge through the rear heads of said stationary cylinders 20 and 21 by way of said valves 48 and 50. As the reciprocating cylinder 29 completes its rearward or inward movement or stroke, the slide plate 53 of the valve 43 engages the member 44 and this valve is thus reversed, closing communication between the interior of the main compressed air tank 11 and the rear end of the reciprocating cylinder 29 but opening communication between the interior of the rear end of the reciprocating cylinder 29 and the air conducting tube 40, permitting this charge of compressed air to pass by way of the air conducting tube 40 into the air chamber 49 between the stationary cylinders 20 and 21. The valve 46 is also closed by the end 41 of the air conducting pipe 40 and valves 47 and 45 are opened by the pistons 34 and 37, respectively as the reciprocating cylinder 29 completes its rearward or inward stroke. At the same time the piston 34 engages the valve 47 and opens the latter, while the piston 37 engages the valve 45 and opens the same. Thus

the first rearward stroke of the reciprocating cylinder 29 is completed.

Now the compressed air in the air chamber 49 passes through the open valve 47 into the stationary cylinder 20, rearwardly of the piston 34 and forces the latter forwardly. At the same time the compressed air within the rear end of the reciprocating cylinder 29 passes through the opened valve 45 into the stationary cylinder 21, rearwardly of the piston 37 and presses forward against the latter. During the first forward stroke of the reciprocating cylinder 29 and the pistons 34 and 37, the air previously drawn into these stationary cylinders 20 and 21, forwardly of the reciprocating pistons 34 and 37 is compressed. As this air in the forward end of the stationary cylinders 20 and 21 is compressed sufficiently during this forward stroke, the automatic check valves 36 and 39 are thus forced to open and permit this air to pass to the other side of the pistons 34 and 37, the air passing through the valve 36 into the stationary cylinder 20, rearwardly of the piston 34, while the air passing through the valve 39 travels through the hollow piston rod 38 and into the rear end of the main compressed air tank 11. At the end of the forward stroke, the valve 43 is again shifted or reversed to open communication between the interior of the main compressed air tank 11 and the rear end of the reciprocating cylinder 29 and to close the pipe 40. At the same time the valve 45 is closed, the valve 46 is opened by the piston 37, and the valve 47 is closed by the forward end 41 of the pipe 40. It will be seen that on the completion of this second or rearward stroke, the original charge of air from the main compressed air tank 11 has passed from within the rear end of the reciprocating cylinder 29 into the central air chamber 49 and into the stationary cylinders 20 and 21, rearwardly of the reciprocating pistons 34 and 37 and has thus been divided among these three chambers.

All of the parts of the air compressor are now ready for the beginning of the second rearward stroke of the reciprocating cylinder 29 and each succeeding rearward stroke begins and continues as the new charge of compressed air passes from within the main compressed air tank 11, by way of the valve 43, into the rear end of the reciprocating cylinder 29. During its second rearward stroke, the compressed air within the stationary cylinder 20, rearwardly of the piston 34, is forced out of the cylinder 29, through the valve 48, into the central air chamber 49 and passes with the air already in said air chamber 49, through the open valve 46 and into the stationary cylinder 21, forwardly of the piston 37, without effectively opposing the rearward movement of the reciprocating cylinder 29 and the pistons 34 and 37. The compressed air within the stationary cylinder 21, before the beginning of this second or new rearward stroke is, during the second or new rearward stroke forced by the piston 37 through the valve 50 and into the rearwardly moving end of the reciprocating cylinder 29. A supply of atmospheric air is also drawn into the stationary cylinder 20 by the piston 34 on its rearward movement. When the second or new rearward stroke of the reciprocating cylinder 29 is being completed, the valve 43 is again reversed, closing communication between the main compressed air tank 11 and the rear end of the reciprocating cylinder 29 and opening communication between said rear end of the

reciprocating cylinder 29 and the air conducting pipe 40, thus reversing of the valve 43 being again accomplished through the medium of the member 44. At the same time, the valve 45 is again opened by the piston 37, the valve 46 is closed by the end 41 of the pipe 40 and the valve 47 again opened by the piston 34. The parts of the air compressor are now ready for the second or new forward stroke of the reciprocating cylinder 29 and the pistons 34 and 37.

During the second forward stroke, the second charge passes from the rear end of the reciprocating cylinder 29 through the pipe 40 into the central air chamber 49 and also through the open valve 45 into the stationary cylinder 21, rearwardly of the piston 37 to operate on the latter and force the same forwardly. The valve 41 being also open, the air from the central air chamber 49, now of increased pressure, passes through the open valve 47, into the stationary cylinder 20 and presses against the rear face of the piston 34 therein during the following forward movement of the latter. The compressed air in front of the piston 34 passes through the valve 36 therein, to the rear side of the piston 34 and any excessive air pressure within the rear portion of the stationary cylinder 20, over the pressure within the central air chamber 49 will result in the opening of the valve 49 and equalization of the air pressure within said rear portion of the stationary cylinder 20 and within the central chamber 49. The compressed air in the stationary cylinder 21, forwardly of the piston 37, passes by way of the valve 39, through the hollow piston stem 38 into the rear portion of the main compressed air tank 11, during the second or new forward stroke of the reciprocating cylinder 29, and the pistons 34 and 37.

During each forward stroke of the reciprocating cylinder 29 and the pistons 34 and 37, the compressed air within the main compressed air tank 11 tends to exert pressure on the broad outer face of the rear end of the reciprocating cylinder 29. Likewise, during each rearward stroke of the reciprocating cylinder 29 and the pistons 34 and 37, the compressed air within the main compressed air tank 11 tends to exert pressure on the forward end of the reciprocating cylinder 29 and the forward face of the flange 31 of the rear end thereof.

As the following rearward and forward strokes of the reciprocating cylinder 29 and the pistons 34 and 37 are in accordance with the second rearward and forward strokes, as described in detail, all of the valves operating in the manner set forth, on all of the succeeding strokes, the operation should now be clear and without need for further detailed description.

The single arrows applied to Figures 1 and 2, of the drawings, indicate the valves which open on each rearward stroke of the reciprocating cylinder 29 and the direction in which the air passes through said valves. The double arrows indicate the valves which open on each forward stroke of the reciprocating cylinder 29 and the direction in which the air travels through such valves.

From the foregoing description, taken in connection with the accompanying drawings, it will be manifest that an air compressor is provided that will fulfill all the necessary requirements of such a device, but as many changes could be made in the above description and many apparently widely different embodiments of my invention constructed within the scope of the ap-

pended claims, without departing from the spirit or scope thereof, it is intended that all matters contained in the said accompanying specification and drawings shall be interpreted as illustrative and not in a limiting sense.

Having thus described my invention, what I claim as new and desire to secure by Letters Patent is:—

1. An air compressor including a compressed air tank; a reciprocating cylinder and pistons within said tank; stationary cylinders suspended in said tank and within said reciprocating cylinder; said pistons operating in said stationary cylinders; and control valves for said compressor.

2. An air compressor including a main compressed air tank; stationary cylinders suspended in spaced relation within said tank; a reciprocating cylinder working over said stationary cylinders within said tank; pistons working with said reciprocating cylinder and operating in said stationary cylinders; guide means for said reciprocating cylinder; an operating handle for reciprocation of said reciprocating cylinder; and control valves for said air compressor.

3. An air compressor including a main compressed air tank; a pair of stationary cylinders suspended in spaced relation centrally in said tank; a cylinder reciprocated longitudinally on said stationary cylinders; the space between said stationary cylinders and within the reciprocating cylinder serving as a central compressed air chamber; guide means for said reciprocating cylinder; pistons connected with said reciprocating cylinder and operating within said stationary cylinders; means for forming communication between one end of said reciprocating cylinder and said central compressed air chamber; and controlling valves for said air compressor.

4. An air compressor including a main compressed air tank; a reciprocating cylinder operating longitudinally therein; guide means for said cylinder; pistons carried by and operable with said reciprocating cylinder; a pair of comparatively small stationary cylinders suspended within said reciprocating cylinder with an auxiliary central air chamber therebetween; valves for each of said cylinders and pistons; and manual operating means for said reciprocating cylinder.

5. An air compressor including a main compressed air tank having an extension; a pair of stationary cylinders suspended in spaced alignment within said tank and connected with the extension thereof; a reciprocating cylinder within said tank and working on said stationary cylinders; guide means for said reciprocating cylinder; said reciprocating cylinder also working on the extension of said main compressed air tank and on said stationary cylinders; pistons carried by said reciprocating cylinder and working within said stationary cylinders; and mechanically controlled valves and check valves for said cylinders and pistons; said mechanically controlled valves being opened and closed mechanically at the end of each stroke of said reciprocating cylinder and pistons.

6. An air compressor including a main compressed air tank; connected stationary cylinders suspended in alignment, in the center of said tank; supporting means for said stationary cylinders connected with one head of said tank; a reciprocating cylinder working on said stationary cylinders and enclosing the latter; guide means for said reciprocating cylinder carried by the other head of said tank; said reciprocating cylinder having an extension working through

the first mentioned head of said tank and enclosing and operating on said supporting means for the stationary cylinders; pistons carried by said reciprocating cylinder and working within said stationary cylinders; mechanically controlled valves and check valves for said cylinders and said pistons; and means working with said reciprocating cylinder for controlling said mechanically controlled valves.

7. An air compressor including a main compressed air tank; a reciprocating cylinder operating longitudinally within said tank; guide means for said reciprocating cylinder; stationary cylinders arranged in spaced relation and supported in said reciprocating cylinder; mechanically controlled valves and check valves for said cylinders and said pistons; an air conducting pipe forming communication between one end of said reciprocating cylinder and the air chamber formed within said reciprocating cylinder between said stationary cylinders; one of said valves serving to control passage of air through said pipe; said pipe serving to operate on mechanically controlled valve for each of said stationary cylinders; the said check valves being normally closed and opened only by air pressure; and means for reciprocating said reciprocating cylinder.

8. An air compressor including a main com-

pressed air tank; a reciprocating cylinder operating longitudinally in said tank; said reciprocating cylinder having a flanged end; guide means carried by one head of said tank and cooperating with the flanged end of said reciprocating cylinder to guide the same; an extension carried by said reciprocating cylinder at its opposite end and working through the other head of said tank; stationary cylinders arranged in spaced alignment within said reciprocating cylinder and connected with one another; means extending from a head of one of said stationary cylinders and projecting through the extension of said reciprocating cylinder and connected with the adjacent head of said tank to support said stationary cylinders in suspended position; said stationary cylinders and said reciprocating cylinder containing initially only atmospheric air; a valved air inlet from the atmosphere to one of said stationary cylinders; automatically operated valves for said cylinders; pistons carried by said reciprocating cylinder and working in said stationary cylinders; valves for said pistons; and means for causing automatic opening and closing of said automatically operated valves at the end of each stroke of said reciprocating cylinder.

RUSSELL J. REANEY
